(57) **CLAIM**

The ornamental design for a cutting tool for tree pruning, as shown and described.

DESCRIPTION

FIG. 1 is a top perspective view of the first embodiment of the claimed design;

FIG. 2 is front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of the second embodiment of the claimed design;

FIG. 9 is front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines rendered in embodiment 2 of the drawings illustrate portions of the cutting tool for tree pruning and form no part of the claimed design. The superimposed areas incised in broken lines, shown in embodiment 1 of the drawings, illustrate portions of the cutting tool for tree pruning and form no part of the claimed design.

1 Claim, 8 Drawing Sheets
